COMBINED EMERGENCY ASH TRAY AND MATCH BOX LOCK

Original Filed May 13, 1921

Inventor
Arlington Moore
By Attorney H. H. Dyke

UNITED STATES PATENT OFFICE.

ARLINGTON MOORE, OF NEW YORK, N. Y., ASSIGNOR TO MOORE INVENTIONS CORPORATION, OF WORCESTER, MASSACHUSETTS, A CORPORATION OF MASSACHUSETTS.

COMBINED EMERGENCY ASH TRAY AND MATCH-BOX LOCK.

Application filed May 13, 1921, Serial No. 469,166. Renewed January 7, 1927.

My invention relates to a combined emergency ash tray and match box lock.

Smokers frequently experience a need for an emergency ash tray for ashes, burnt matches, etc., as when smoking in a parlor, for example.

Match boxes as ordinarily constructed often open up in the pocket, particularly when the box is only partially filled with matches.

My invention provides an emergency ash tray in combination with a match box. When the ash tray is not in use it is folded up, and in the folded position lies close to the match box taking up substantially no extra room and provides a lock to keep the match box closed.

Certain of the numerous embodiments which may be made of my invention are shown in the accompanying drawings in which Fig. 1 is a perspective view of a match box provided with an attachment in accordance with my invention, said attachment being shown in the open position and adapted to serve as an emergency ash tray. Fig. 2 is a perspective view similar to Fig. 1, but showing the attachment in folded position and adapted to serve as a lock for keeping the match box closed. Fig. 3 is a transverse cross-sectional view illustrating one form of construction. Fig. 4 is a view similar to Fig. 3 but showing the parts in the closed position instead of in the open position as in Fig. 3. Fig. 5 is a view similar to Fig. 3 but illustrating a modified form of construction, and Fig. 6 is a plan view showing the tray opened out and showing how the ends of the tray are adapted to "hug" the box when closed.

Reference character 10 designates the match receptacle, and 11 the casing in which the receptacle 10 containing matches is slidably received in the usual manner. Emergency tray and lock member 12 is hinged to the casing 11 in any suitable manner. In Fig. 3 the bottom 13 of casing 11 is continued to form the member 12 and the hinge is produced by making a fold line or crease 14 at the corner of the casing 11. In Fig. 5 the tray-lock member 12' is made separately from the casing 11, and the label 15 pasted on the bottom of the casing and tray affords the hinged connection, and a similar result may be obtained in yet other ways.

The tray-lock member 12 or 12' comprises

the bottom wall 16, the side wall 17 and the end walls 18, 18. The bottom wall 16 of the tray is advantageously of a width substantially equal to the height of the match box, so that the tray-lock member 60 can fold over the match box and lie close and snug thereagainst. The side wall 17 may be of any height. It is advantageously of height less than the width of the match box, and is preferably of about the same 65 height as the match box itself. The end walls 18, 18 may advantageously be made so as to grip or hug the ends of the box when turned to the closed or locked position, shown in Figs. 2 and 4, so that the lock 70 member will remain in such position until turned into the open or tray position, as shown in Figs. 1, 3 and 5. This may be accomplished by making the distance between end walls 18, 18 slightly less than the 75 length of the tray, as shown in Fig. 6. Turning the tray-lock member upon its hinge for folding or unfolding, of course, requires the application of only a very slight amount of force, but a frictional engagement is desirably secured so that such member when in folded position will tend to remain in that position.

It will be seen that a match box embodying my invention may be positively locked 85 in closed position, thereby preventing spilling of the matches in the pocket; and that the locking device fits closely to the box and takes up substantially no additional space, and does not interfere in any way with 90 the packing of the folded match box in cartons or other containers; and that the hinged attachment of the present invention when opened up provides an emergency tray readily available for the temporary reception of 95 ashes, matches, cigar bands and the like, and as soon as same have been emptied out, the tray can be folded up to fit about the box and provide a lock therefor. Also the tray-lock member may be used to shield a match 100 when lighted in the wind, without danger of igniting the matches in the box, which may be entirely closed.

The forms shown are for illustration and for affording an understanding of my invention only, and modifications and changes may be resorted to without departing from the principle of my invention.

I claim:

1. A match box having a tray hinged 110

thereto, the end walls of the tray being adapted to grip the box when turned on its hinge.

2. In a match box, a casing open at its ends, a match receiver slideable therein, and a tray hingedly attached to the casing to turn on an axis parallel to direction of movement of the receiver and adapted when turned inwardly on its hinge to retain the receiver in its place in the casing.

3. In a match box, an open ended casing, a match receiver normally slideable therein,

a tray hinged to the casing bottom at one side thereof and having ends free at an edge thereof, said tray being adapted to fold over the casing with the end walls in hugging relation to the match receiver therein, whereby the receiver is locked in position and the tray is frictionally held in folded relation to the rest of the box.

In testimony that I claim the foregoing, I have signed my name hereto.

ARLINGTON MOORE.
